MOUNTING FOR WELDERS' HELMETS, FACE SHIELDS AND THE LIKE

Charles Evans Bowers, Sr., Moylan, Pa., assignor to The Fibre-Metal Products Company, Chester, Pa., a corporation of Pennsylvania

Application May 31, 1956, Serial No. 588,504

4 Claims. (Cl. 24—211)

This invention relates to mountings for welders' helmets, face shields, and the like.

It has heretofore been proposed to pivotally connect a welder's face shield or helmet to a head carried element, such as a welder's hat or safety hat, so that the face shield or helmet could be swung from a downwardly disposed position for use to an upwardly disposed and out-of-use position.

The connections heretofore available were difficult to assemble, were not readily detachable and had other objectionable characteristics.

It is the principal object of the present invention to provide an improved mounting for welders' helmets, face shields and the like which permits the face shield or helmet to be readily shifted from a position for use to an out-of-use position and which will permit the quick detachment and reattachment of the face shield or helmet, if desired.

It is a further object of the present invention to provide an improved mounting for welders' helmets, face shields and the like which overcomes the difficulties encountered with the devices heretofore available.

It is a further object of the present invention to provide a mounting for welders' helmets, face shields and the like which is simple yet sturdy in construction, and which can be readily applied to helmets and face shields now in use.

It is a further object of the present invention to provide a mounting for welders' helmets, face shields and the like, with which the interconnected parts can be readily detached and the operation of which will be readily understood by the user.

Other objects and advantageous features of the invention will be apparent from the specification and claims.

The nature and characteristic features of the invention will be more readily understood from the following description, taken in connection with the accompanying drawings forming part thereof, in which:

Figure 1 is a top plan view of a safety hat and welding helmet with the mounting in accordance with the invention therebetween;

Fig. 2 is a vertical sectional view taken approximately on the line 2—2 of Fig. 1, and showing the helmet in its downward position for use;

Fig. 3 is a view similar to Fig. 2, but showing the helmet in its upward out-of-use position;

Fig. 4 is a fragmentary vertical sectional view taken approximately on the line 4—4 of Fig. 1;

Fig. 5 is a sectional view taken approximately on the line 5—5 of Fig. 4;

Fig. 6 is an exploded view in perspective of one portion of the mounting in accordance with the invention, parts being broken away to illustrate the internal construction; and

Fig. 7 is an exploded view in perspective of another portion of the mounting in accordance with the invention.

It should, of course, be understood that the descrip-

2

tion and drawings herein are illustrative merely, and that various modifications and changes can be made in the structure disclosed without departing from the spirit of the invention.

5 Like numerals refer to like parts throughout the several views.

Referring now more particularly to the drawings a safety hat 10 of well known type is illustrated, and is adapted to be supported and held upon the head of the user in any desired manner. The hat 10 can be of vulcanized fibre or any other suitable material and can have along one marginal edge portion thereof a visor 11 which is rearwardly disposed for one character of use of the invention and serves to protect the back of the neck of the user. The hat 10 has downwardly extending substantially vertical side walls 12 with an outwardly disposed rim 13 therebelow.

A welder's helmet is shown at 15, is provided with the customary rectangular frame 16 for the reception 20 of a lens and protective cover glass (not shown) and has oppositely disposed side walls 17. The helmet 15 can be made of vulcanized fibre or any other suitable material.

The mounting 18, hereinafter more fully described, 25 employed to interconnect the hat 10 and the helmet 15 is shown in detail in Figs. 4, 5, 6 and 7.

The side portions 12 of the hat 10, intermediate the front and the rear of the hat 10, preferably each has secured thereto, by screws 20 extending therethrough, a 30 projecting mounting block 21, which can be cylindrical and circular in cross section, forming part of the mounting 18.

The mounting blocks 21 preferably have their inner faces 22 inclined to conform to the slope of the side 35 portions 12 and are mounted so that the longitudinal axes of the mounting blocks 21 will be disposed in alignment. The blocks 21 can be made of any desired material, resins of the phenol formaldehyde type being suitable.

40 The mounting blocks 21 each has a transverse bore 23 with an interior shoulder 24 and an extension 25 of reduced diameter, the opposite end 26 of the bore 23 being threaded.

A locking pin 27 is provided in the bore 23 and has a shoulder 28 for limiting the outward movement of the pin 27, as determined by the shoulder 24, and to serve as an abutment for a spring 29 which normally urges it outwardly. The spring 29 abuts, at its other end, against a threaded plug 30. The plug 30 is in threaded engagement in the threaded end 26 of the bore 23.

45 The locking pins 27 each has an end portion 31 normally extending outwardly beyond the bore extension 25 and has a part 32 of reduced diameter adjacent its terminal or free end for purposes to be explained.

The side portions 17 of the shield 15 have opposed 55 sockets 35 mounted thereon for the reception of the mounting blocks 21. The sockets 35 are complementary in shape to the mounting blocks 21, in the side wall portions thereof have locking slots with inner circular portions 36 of a diameter corresponding to that of the end portion 31 of the pin, and slots 37 extending to the outer edges of the sockets 35 of a width corresponding to the diameter of the pin part 32.

The pins 27 normally have end portions 31 engaged 65 in the slot portions 36 to hold the sockets 35 in position on the mounting blocks 21. Separation of the sockets 35 from the mounting blocks 21 can be effected by pressing the pins 27 inwardly, against the force of the springs 29, to bring the parts 32 to a position at the slots 37 thereby to permit the axial separation of the sockets 35 from the mounting blocks 21.

70 The sockets 35 can be mounted on the interior of the

side walls 17 of the shield 15 in substantial axial alignment in any desired manner but it is preferred to provide an adjustable connection, on each side of the shield 15, to regulate the freedom of turning of the side walls 17 with respect to the sockets 35.

For this purpose, a stud 40 is provided on each side having an enlarged disc head 41, a square or other non-circular shaped shank 42 and a threaded end 43. The head 41 is adapted to engage with a friction washer 44 which in turn engages with the inner face of the flange 45 at the inner end of the socket 35. A friction washer 46 is provided in engagement with the outer face of the flange 45 and with the inner face of the side wall 17. The noncircular shank 42 is preferably in engagement with a complementary opening 47 in the side wall 17 to prevent the turning of the stud 40.

On the stud 40, and in contact with the outer face of the side wall 17, a metallic washer 48 is provided for engagement by a spring washer 49. The threaded end 43 extends through the washers 48 and 49 for engagement by an adjusting nut 50. By turning of the nut 50, the frictional drag imposed upon the turning of the supports for the sockets 35 and accordingly the freedom of movement of the face shield, can be varied to suit the desires of the user.

It will be seen that with the sockets 35 in locked engagement on the mounting block 21, the helmet 15 can be raised or lowered as desired, and by reason of the adjustable frictional drag imposed upon the sockets 35 the desired degree of tightness and frictional holding can be quickly attained by adjustment of the nuts 50.

If, at any time, it is desired to separate the helmet 15 from the hat 10, for use of the hat 10 alone, or for any other purpose, this can be readily effected by pressing the pins 27 inwardly to their releasing positions and separating the sockets 35 from the mounting blocks 21. The resilient character of the helmet 15 is such that no difficulty is encountered in separating the wall portions 17 to the required extent. The helmet 15 can be quickly reattached to the hat 10 by a reverse of the operations required for separation.

I claim:

1. In combination, a first member, a second member in spaced relation to said first member, and connecting means for connecting said members for relative rotation and for a quick detachable axial separation comprising a mounting projection secured to the exterior of said first member, a separable socket device axially aligned with said projection for the reception of said projection, said socket device and said projection being disposed between said members, interengaging portions on said projection and said socket device for releasably retaining said projection and socket device against axial separation, a member having a portion in rotatable engagement with said socket device and a portion extending through said second member, and adjusting means on said last member exteriorly disposed with respect to said second member for adjusting the freedom of rotatability of said first and second members.

2. In combination, a first member, a second member in spaced relation to said first member, and connecting means for connecting said members for relative rotation and for quick detachable axial separation comprising a mounting projection secured to the exterior of said first

5 member, a separable socket device axially aligned with said projection for the reception of said projection, said socket device and said projection being disposed between said members, interengaging portions on said projection and said socket device for releasably retaining said projection and said socket device against axial separation, a member having a portion in rotatable engagement with said socket device and a portion extending through said second member and having an outer threaded end, and adjusting means on said threaded end exteriorly disposed with respect to said second member for adjusting the rotatability of said first and second members.

3. In combination, a first member having a flat side portion, a second member having a flat side portion in spaced relation to said first mentioned side portion, and connecting means for connecting said members at said side portions for relative rotation and for quick detachable axial separation comprising an outwardly extending mounting projection secured to the exterior of said first mentioned side portion, a separable socket device axially aligned with said projection for the reception of said projection, said socket device and said projection being disposed between said portions, interengaging locking portions on said projection and said socket device for releasably retaining said projection and socket device against axial separation, a stud having a head in rotatable engagement in said socket device and a shank portion axially aligned with said socket device and extending through said second member flat portion in locked engagement with respect thereto, and adjusting means on said shank exteriorly disposed with respect to said second member for adjusting the freedom of rotatability of said first and second members.

4. In combination, a first member having a flat side portion, a second member having a flat side portion in spaced relation to said first mentioned side portion, and connecting means for connecting said members at said side portions for relative rotation and for quick detachable axial separation comprising an outwardly extending mounting projection secured to the exterior of said first mentioned side portion, a separable socket device axially aligned with said projection for the reception of said projection, said socket device and said projection being disposed between said portions, interengaging locking portions on said projection and said socket device for releasably retaining said projection and socket device against axial separation, a stud having a head in rotatable engagement in said socket device and a shank portion extending through said second member flat portion in locked engagement with respect thereto, said shank portion having a threaded end, and adjusting means on said threaded end exteriorly disposed with respect to said second member for adjusting the freedom of rotatability of said first and second members.
